UNITED STATES PATENT OFFICE

2,652,024

SPRAYING MECHANISM FOR LIVESTOCK CARS

James M. Coyner, Madison, Wis.

Application December 26, 1951, Serial No. 263,295

3 Claims. (Cl. 119—7)

1

This invention relates to a livestock car and spraying mechanism.

The present application is a continuation-in-part of my co-pending application, Serial No. 241,011, filed August 9, 1951.

The equipment of a livestock car with efficient watering, feeding, etc. equipment has long presented a serious problem. Suggestions have been made for raising troughs above the floor, introducing water into troughs, and for spraying water on to hard floors, but the equipment has not been able to withstand the severe jolting and hammering effect of railway travel. When a stock train or freight train stops and starts, there is a severe jerking and jolting of the cars, and any equipment within the cars is subjected to heavy blows which tend to destroy the equipment or to batter the car walls. While the suggestions have been made, no one has heretofore produced a livestock car equipped with such feeding and watering devices which could be successfully employed, and up to the present time it has remained the practice to stop the cars periodically in transit, carry troughs into the cars, and after feeding the stock to remove the troughs, or, alternatively, to drive the stock from the cars and into feeding lots. The foregoing results in long delays, requires considerable labor, and has long been unsatisfactory.

The wetting of stock by sprays has been found unsatisfactory and an unhealthy procedure. An atomized spray or mist-like application of water is not injurious, but is desirable. However, up to the present time, no means has been provided for the application of moisture in this manner.

An object of the present invention is to provide a livestock car equipped with feeding and watering means and with means for applying an atomized spray of water to the stock, while at the same time providing means which stabilize and protect the troughs in their lowered and elevated positions and while also facilitating the raising and lowering of the troughs from inside and outside the car. Another object is to equip at least one end of the car with water supply means whereby water can be introduced into a trough while further utilizing the compressed air supply of the car for atomizing water at the end of the car for applying a mist of spray to the stock. Yet another object is to provide in combination with a railway car equipped with compressed air, means whereby the compressed air is utilized in atomizing water to form a spray to apply to the stock carried within the car. Yet

2

another object is to provide a car structure of the character set forth equipped with feeding, watering, and spraying means in the arrangement and for the purposes shown. Other specific objects and advantages will appear as the specification proceeds.

The invention is shown in an illustrative embodiment, by the accompanying drawing, in which the single figure shows a railway car in cross-section equipped with spraying means embodying my invention.

In the illustration given, A designates a livestock car provided with a floor 10, side walls 11, a roof or top wall 12, and an end wall 13. It will be understood that any type of stock car or stock-transporting vehicle may be employed. In the illustration given, the side walls 11 are formed with slats 14 conforming to the usual practice in the fabrication of stock cars. The car may be provided with a single floor or with two floors, and the equipment may be varied for the provision of watering, feeding, and cooling means for the compartments thus formed. The side walls of the car are preferably provided with guide means 15 for supporting troughs 16, the features of such construction being shown more fully in my co-pending application, Serial No. 241,011, filed August 9, 1951.

At one end 13 of the car is supported a large water storage tank 17, which is preferably provided with a filling pipe 18 extending through the roof of the car and provided with a cap 19. A water spray tank 20 is supported below tank 17 upon the beam 21, and is adapted to receive water from tank 17 through the gravity flow pipe 22 controlled by valve 23.

A compressed air tank 24 is supported in the upper portion of the car adjacent the tanks 17 and 20, and compressed air is supplied to the tank through the pipe 25 leading to a compressed air reservoir 26 at the bottom of the car A.

If the car is a railway car, the pipe 25 may connect with the usual compressed air tank employed for supplying compressed air for brakes. If the car is a truck or other type of gas-propelled vehicle, the compressed air tank ordinarily carried by such vehicles may be connected with the pipe 25. A check valve 27 may be employed to prevent the escape of gas pressure from tank 24 and, if desired, the pipe 25 may be provided also with a manually-operable valve 28.

Connecting the compressed air tank 24 and the water-filled tank 20 is a pipe 29, provided with a control valve 30.

55 Spray pipe apparatus is preferably connected

to the tank 20 and is extended across one end or longitudinally of the car, as desired. In the illustration given, a pipe 31 extends along one end of the car and then forwardly longitudinally of the car, and the pipe is provided with a plurality of jets 32 through which the water may be discharged under the force of compressed air to form sprays. The pipe 32 is preferably provided with a joint connection 33 permitting the forward pipe portion 34 to be swung laterally across the car for efficient spraying of the stock.

Operation

In the operation of the structure, the tank 20 is filled to the desired extent with water from the tank 17 and then the valve 23 is closed to break the connection between the two tanks. Valve 30 is then opened to allow compressed air to flow into the water spray tank 20. Under such pressure the water is discharged through the spray nozzles 32 to form a mist-like spray upon the stock below. Compressed air from the reservoir 26 flows through pipe 25, check valve 27, and thence into the compressed air tank 24 to keep the tank supplied with sufficient air to bring about the spraying operation to the extent desired.

While the invention has been described herein particularly in connection with a railway livestock car, it will be understood that the invention is likewise applicable to other vehicles or cars such as automobile trucks, etc., and in the use of the term "livestock car" in the appended claims, it will be understood that such term is intended to cover various vehicles used for the transportation of stock.

While in the foregoing specification, I have set forth a specific structure illustrating one embodiment of the invention, it will be understood that such details of structure may be varied 40 widely by those skilled in the art without departing from the spirit of the invention.

I claim:

1. In a livestock car equipped with a compressed air reservoir, a water tank supported in the upper portion of said car, a spray tank supported therebelow and connected to the water tank by a valve-controlled conduit, a compressed air tank communicating with said car reservoir, a valve-controlled conduit connecting said compressed air tank and said water spray tank, and a spray conduit leading from said water spray tank across a portion of said car and equipped with spray orifices therein.

2. In a livestock vehicle equipped with a compressed air line, a water tank supported in the upper portion of the vehicle, a spray tank supported therebelow and connected to the water tank by a valve-controlled conduit, a conduit connecting said compressed air line and said water spray tank, and a spray conduit leading from said water spray tank across a portion of said vehicle and equipped with spray orifices therein.

3. The structure of claim 2, in which said spray conduit has a horizontal portion extending across the vehicle and a second horizontal portion rotatably mounted upon said first-mentioned portion and extending across the vehicle, said conduit portions being provided with spray orifices.

JAMES M. COYNER.
